(57) **CLAIM**

The ornamental design for a computer keyboard, as shown and described.

DESCRIPTION

FIG. 1 is a right, front isometric view of a computer keyboard showing our new design;

FIG. 2 is a left, rear isometric view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left elevational view thereof; and,

FIG. 8 is a right elevational view thereof.

The broken lines are shown in the views for illustrative purposes only and form no part of the claimed design.
